UNITED STATES PATENT OFFICE.

MAGNUS UNGER, OF PITTSFIELD, MASSACHUSETTS, ASSIGNOR TO GENERAL ELECTRIC COMPANY, A CORPORATION OF NEW YORK.

STATIONARY INDUCTION APPARATUS.

Application filed May 26, 1921. Serial No. 472,879.

To all whom it may concern:

Be it known that I, MAGNUS UNGER, a citizen of the United States, residing at Pittsfield, in the county of Berkshire, State 5 of Massachusetts, have invented certain new and useful Improvements in Stationary Induction Apparatus.

My invention relates to stationary induction apparatus and has for its general object an improved economical, and readily 10 manufactured arrangement of parts.

More particularly my invention relates to induction apparatus of the type applicable for use in connection with induction 15 furnaces in which the charge constitutes the secondary of the transformer; a specific object being the provision of an arrangement which is rugged and is interlinkable with a furnace crucible.

20 In the induction type of electric furnace, it has generally been customary to employ an open and unprotected inducing winding in order to afford the air, which is generally the cooling medium employed, easy access to such winding. A winding of this construction is particularly disadvantageous in metallurgical work as it is exposed to fumes and dust which may impair or short circuit the turns of the winding. Also it may be 25 wholly destroyed in the event of the crucible itself breaking.

The magnetic core too, in this type of furnace, has generally been constructed in a manner adapted for disassembly, since their 35 removal from the crucible is often desirable; it being the practice to change crucibles whenever their useful life seems impaired, the heating, however, generally being accomplished always with the same induction 40 apparatus. In the construction heretofore employed this disassembly could not be easily or quickly accomplished; a large number of core joints were in the path traversed by the magnetic flux; and altogether a number 45 of loose parts were involved, which did not make for efficiency either mechanically or electrically.

By my invention however these shortcomings are avoided, since I make use of a 50 core composed of separable parts having

substantially a minimum of magnetic joints, the same being secured together in a simple and rugged manner. Moreover, I employ a novel coil construction for the inducing winding which is insulated and protected 55 against fumes, dust and possible breakage of the crucible. My construction, is particularly heat resistive and may be heated for long periods and to very high temperatures without in any manner impairing the construction or insulation qualities of the winding.

For a more complete understanding of the nature and objects of my invention reference should be made to the following 65 detailed description taken in connection with the accompanying drawing in which:

Figs. 1 and 2 are views in perspective, showing first in disassembled and then in assembled positions, a core and inducing 70 winding constructed in accordance with my invention. Fig. 3 is a diagrammatic view showing the induction apparatus of Figs. 1 and 2 applied to a crucible to make an induction furnace; while Fig. 4 is a fragmentary detail view of a winding.

Referring now to the drawing, 10 denotes a U-shaped core member made of laminated magnetic material. This member cooperates with a T-shaped core member 11, also made 80 of laminated magnetic material and has a winding 12 surrounding the leg 13. The T-shaped member is adapted to fit on the upstanding legs of the U-shaped member to form a three-legged core as shown in Fig. 85 2; the T member being held to the U member by means of clamping devices shown respectively at 14, 15 and 16.

A shell type core is thus formed of separable members, each of which comprises 90 both a leg portion and a yoke portion. This is a particularly advantageous construction adapted for handling by cranes in furnace work, since by attaching the crane to the yoke which is easily accessible, the winding 95 which is usually less accessible may at the same time be moved.

Any convenient form of clamps at 14, 15 and 16 may be employed, that shown comprises hook-shaped members 17 which en- 100

gage with recesses 18 formed in strips 19 laid along and secured to the legs of the core. These hook members have threaded shanks which pass through suitable holes 5 in bars 20 which are drawn up against the core by nuts 21 which engage with the threaded shanks.

The arrangement shown yields a three legged core of the butt-joint type which may 10 be assembled and disassembled merely by manipulating the nuts 21. The core member 11 with the winding 12 which is the inducing winding, when disassembled may be inserted readily in the annular breach of 15 a crucible shown at 25 in Fig. 3, to make an induction furnace; the core member 10 having been subsequently attached.

The winding 12 is supported on the leg by the wedging action on insulating rods 27 20 and as previously indicated, is constructed in a rugged manner affording protection against fumes, dust, etc. To this end it is preferably wound edgewise from copper strap as a continuous helical spiral, as indicated in Fig. 4. The turns are insulated from each other by inserting segments of mica or asbestos or each individual turn may be wrapped with this material as shown in 25 Fig. 4; other convenient modes of applying it, however, may be employed. The turn insulation is preferably covered with a refractory cement which will assist in holding the turns in place. The cement is inorganic, heat resistant and electrically insulating. 30 For example, a paste formed by mixing clay or finely ground blast furnace slag with an inorganic binder, such as silicate of sodium, may be used. The coil thus formed is now preferably given an exterior wrapping of 35 asbestos tape which is filed with and covered with a refractory cement indicated at 32. A coil of this construction is mechanically very strong and is well protected from the deleterious action of external agents. Such a 40 coil may be operated continuously at a temperature of 500° C. for periods of time exceeding in duration a week without being impaired in any way.

As a final precaution, however, and in 50 order to provide protection for the coil 12 against the molten metal which may escape in the event of the crucible breaking, I surround it with a metallic cylinder 35 split and separated along some element as indicated at 36, such separation being employed 55 to prevent short circuited current from flowing; the metal of this cylinder being preferably one of low magnetic permeability. The cylinder, fragments of which are shown 60 in Figs. 2 and 4, fits between the coil 12 and the surrounding furnace structures preferably supporting the crucible wall 37 so that the cooling air will pass between the winding and the metallic cylinder as indicated in Fig. 3.

Having now described an embodiment of my invention which is at present the best means known to me for carrying the same into effect, I would have it understood that this is merely illustrative, and that I do not 70 mean to be limited thereby to the precise details shown nor restricted in the choice of recognized equivalents except as defined in my claims hereunto annexed.

What I claim as new and desire to secure 75 by Letters Patent of the United States, is:—

1. Stationary induction apparatus for metal melting furnaces comprising a U shaped core member, a T shaped core member arranged to cooperate with said U shaped core member to form a three-legged core, the middle leg of said core being the leg of said T shaped member, a primary winding surrounding said leg adapted to be inserted in the secondary loop of the crucible of an electric induction furnace, and means for securing said winding to said leg whereby said winding may be moved with said T shaped core member and thereby inserted in and removed from said secondary 90 loop.

2. Stationary induction apparatus for metal melting furnaces comprising a U shaped core member, a T shaped core member arranged to cooperate with said U shaped core member to form a three-legged core, the middle leg of said core being the leg of said T shaped member, a primary winding surrounding said leg adapted to be inserted in the secondary loop of the crucible of an electric induction furnace, a layer 95 of heat refractory cementitious material applied directly to said winding so as to form a part thereof, said heat refractory material forming a continuous protective 100 casing for the turns of said winding, and means for securing said winding to said leg whereby said winding may be moved with said T shaped core member and thereby inserted in and removed from said secondary 105 loop.

3. A winding for electrical induction furnaces comprising electrically conducting turns forming a coil, heat refractory electrically insulating material separating said turns, and a layer of heat refractory, electrically insulating cement applied to the exposed surfaces of said turns so as to form a heat refractory electrically insulating 115 coating enclosing said coil.

4. A winding for electrical induction furnaces comprising electrically conducting turns forming a coil, layers of mica separating said turns, and a layer of asbestos and heat refractory electrically insulating cement applied to the exposed surfaces of said turns forming a heat refractory electrically insulating coating completely enclosing said coil.

5. A winding for electrical induction 130

metal melting furnaces comprising flat helical conducting turns, layers of mica separating said turns, a layer of heat refractory electrically insulating cement applied to the exterior of said turns forming a continuous coating around said turns as a whole, a wrapping of asbestos tape applied over said

coating of heat refractory cement, and a layer of heat refractory electrically insulating cement covering and filling said tape. 10

In witness whereof, I have hereunto set my hand this twenty-third day of May, 1921.

MAGNUS UNGER.
